UNITED STATES PATENT OFFICE.

JOSEPH MESSINA, OF BENLD, ILLINOIS.

ACETYLENE-LAMP.

1,219,980.

Specification of Letters Patent. Patented Mar. 20, 1917.

Application filed August 10, 1915. Serial No. 44,767.

To all whom it may concern:

Be it known that I, JOSEPH MESSINA, a citizen of the United States, residing at Benld, in the county of Macoupin and State 5 of Illinois have invented new and useful Improvements in Acetylene-Lamps of which the following is a specification.

The invention relates to miners' lamps and more particularly to the class of acetylene 10 gas lamps for use by miners.

The primary object of the invention is the provision of a lamp of this character wherein in the construction thereof is novel in form so as to keep the gas pure as it is delivered 15 to the burner tip.

Another object of the invention is the provision of a lamp of this character wherein in the feed of water from the reservoir to the carbid container is regulated at will, 20 thereby varying the production of gas during the use of the lamp.

A further object of the invention is the provision of a lamp of this character wherein in the water feed tube is constructed so as 25 to avoid the accumulation of dirt therein and to prevent the clogging or choking of the same, which would interfere with the feed of the water from the reservoir to the carbid container of the lamp.

A still further object of the invention is the provision of a lamp of this character which is simple in construction, thoroughly reliable and efficient in its operation, strong, durable and inexpensive of manufacture.

With these and other objects in view, the invention consists in the construction, combination and arrangement of parts as will be hereinafter described, illustrated in the accompanying drawings, and pointed out in 40 the claim hereunto appended.

In the drawing:

Figure 1 is a side elevation of a lamp constructed in accordance with the present invention;

45 Fig. 2 is a top plan view thereof;

Fig. 3 is a vertical longitudinal sectional view of the same;

Fig. 4 is a sectional view on the line 4—4 of Fig. 3;

50 Fig. 5 is an enlarged fragmentary vertical sectional view through the water tube valve and water feed tube;

Fig. 6 is a side view of the annular hood or housing removed from the lamp; and

55 Fig. 7 is a bottom plan view thereof.

Similar characters of reference indicate

corresponding parts in all the views of the drawing.

Referring to the drawing in detail, the lamp comprises a body A including an upper water reservoir 10, and a lower carbid container or holder 11, the same being formed with a contracted externally threaded neck 12 detachably engaged in the lower sleeve-like portion 13 of the water reservoir 10 for connecting the same. Formed in the reservoir 10 below the bottom 14 thereof is a gas circulating chamber 15, while depending from and integral with the said bottom 14, centrally thereof, is a 70 water feed tube 16 which protrudes into the container or holder 11 for supplying water from the reservoir to the same. Removably fitted within the neck 13 of the container or holder 11 is a disk 17 which has integrally formed therewith at its upper side a circular or annular hood or housing 18 which is concentrically disposed about the water tube 16 and is formed with an externally threaded central apertured sleeve 80 for detachable engagement with the external threaded enlarged portion 19 of the water tube 16, while depending from the lower side of the said disk 17 is a tubiform guard or cage 20 which is disposed concentrically 85 about the water tube 16 and is split at its lower end to form semi-circular wings 21 to enter the body of carbid within the container or holder 11 for the production of gas.

Formed in the disk 17 and establishing 90 communication between the container or holder 11 and the housing or hood 18 is an opening 22 and into which is received one end of a round wick 23 which is coiled within the housing or hood 18 and contains a 95 central wire core 24 which serves to hold the wick 23 in its coiled formation. This wick 23 serves as a conductor for the gas from the container or holder 11 and has its opposite end protruded through an opening 25 formed in the peripheral wall of the said hood or housing 18 for admitting the gas to the circulating chamber 15 for the supply thereof to the burner 26 having fitted therein the tip 27 of the ordinary well known 100 construction. This wick 23 serves to purify the gas consumed at the burner of the lamp.

Formed on the top of the reservoir 10, centrally thereof, and internally of the said reservoir, is a depending boss 28 in which 110 is adjustably threaded a valve stem 29 formed with an inner valve end 30 which

engages the end of the water feed tube 16 on the turning of the stem 29 in one direction, while on turning it in the opposite direction the valve end 20 will be disengaged 5 from the end of the water tube 16 and in this manner the feed of water from the reservoir 10 to the container or holder 11 is regulated. On the outer end of the stem 29 is a finger arm or lever 31 so that the 10 stem 29 can be readily turned by the hand of the user of the lamp.

Formed on the top of the reservoir 10 is a filling nipple 32 closed by means of a hinged cap 33, and through this nipple is 15 adapted to be introduced water into the reservoir. Located about the neck 12 of the container or holder 11 is a rubber gasket 34 which forms a tight joint between the sleeve-like portion 13 of the reservoir and 20 the said container or holder. Likewise, concentrically disposed about the hood or housing 18 and working against the circular flange 35 formed interiorly of the sleeve-like portion 13 of the reservoir 10 is a rubber 25 gasket 36 which forms a tight joint between the disk and the said flange so as to avoid leakage of the gas through the joint between the container or holder 11 and the gas chamber 15 in the reservoir 10 of the lamp. 30 It will be apparent that the opening 22 which receives the wick 23 is completely occupied by the wick so that the gas from the holder 11 will have to permeate the wick before it is delivered to the burner tip. 35 From the foregoing it is thought that the construction and manner of operation of the device will be understood and, therefore,

a more extended explanation has been omitted.

Having thus described my invention, I 40 claim:

A carbid lamp including a water receptacle, a carbid container detachably connected with said receptacle, the water receptacle being formed to provide a water 45 containing section, and a gas circulating chamber arranged below said water containing section and closed against the same, a water delivery tube extending from the water section of the receptacle through and 50 beyond the gas chamber, a gas receiver comprising an independent element centrally formed with a sleeve-like extension to encircle the tube and adapted to be removably connected with said tube, and an annular 55 hollow head carried by the sleeve extension, and fitting within the gas chamber, said annular head having a transverse partition, and being formed with an opening on one side of said partition to establish communication between the head and carbid container, and an opening on the opposite side of the partition to establish communication between the head and gas chamber, and a wick arranged in the head with its terminals 60 on opposite sides of the partition, and immediately adjacent the respective openings.

In testimony whereof I affix my signature in presence of two witnesses.

JOSEPH MESSINA.

Witnesses:

HAZEL BRADLEY,
C. R. EAGLE.
